US0D1062282S

(12) **United States Design Patent** (10) **Patent No.:** **US D1,062,282 S**
(45) **Date of Patent:** **** Feb. 18, 2025**

(54) **REFRIGERATOR ORGANIZER BIN**

(71) Applicant: **Shenzhen Dingtaifu precision Industry Co., LTD**, Shenzhen (CN)

(72) Inventor: **Yong Chen**, Shenzhen (CN)

(73) Assignee: **Shenzhen Dingtaifu precision Industry Co., LTD**, Shenzhen (CN)

(**) Term: **15 Years**

(21) Appl. No.: **29/936,420**

(22) Filed: **Apr. 9, 2024**

(51) LOC (15) Cl. **06-06**
(52) U.S. Cl.

USPC **D6/515**; D3/304

(58) **Field of Classification Search**

(57) **CLAIM**

The ornamental design for a refrigerator organizer bin, as shown and described.

DESCRIPTION

FIG. 1 is a front perspective view of a refrigerator organizer bin, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another front perspective view thereof, shown in a state of use.

The broken lines in the drawings illustrate portions of the refrigerator organizer bin that form no part of the claimed design.

1 Claim, 9 Drawing Sheets
